mesne assignments, to United States of
America

Application February 22, 1944, Serial No. 523,415

2 Claims. (Cl. 60—35.6)

1

This invention relates to projectiles and devices of the type adapted to be projected through space by the reaction propulsion principle.

Various devices of the reaction propulsion or rocket type have been heretofore proposed, among which there is one type which embodies a tubular casing secured to the rearward end of the projectile proper for housing the propelling charge and having its trailing end contoured to provide an axially opening Venturi passage. In such a device, the gases flowing through the Venturi passage, due to uneven burning of the charge, or for other reasons, may flow slightly off center through the Venturi passage. Such off-center flow or shifting of the flow of gases from truly axial flow during the flight of the projectile will cause the projectile to deviate from a true predetermined course.

The object of the present invention is to provide a new and novel arrangement whereby to insure an even flow of gases from a rocket type projectile.

Another object is to provide a rocket type projectile with a rotary gas discharging device adapted to provide for uniform axial flow of the propelling gases.

A further object is to provide a novel arrangement for preventing premature bursting of the casing which houses the propelling charge.

With the above and other objects in view, which will be apparent from the following descriptions to those skilled in the art to which the invention appertains, the present invention consists of certain features of construction and combinations of parts to be hereinafter described with reference to the accompanying drawing, and then claimed.

In the drawing which illustrates a suitable embodiment of the present invention:

Figure 1 is a side elevation, partially in section, of the rocket projectile,

Figure 2 is an enlarged rear end view of the projectile shown in Figure 1, and

Figure 3 is a transverse section taken approximately on line 3—3 of Figure 2.

Referring to the accompanying drawing, the rocket device selected for illustration includes a main projectile body 5 having a chamber 6 for the reception of an explosive or other charge. A tubular casing 7 is threadably or otherwise suitably secured to the rearward end of the body 5, the casing having an internal shoulder 8 which supports a plate-like member 9. The plate-like member 9 supports a cage, composed of the rods 10 and interconnecting end

2

ring 11, which carries the propelling charge, which as shown in the drawing may be in the form of sticks 12 of slow-burning powder or other suitable combustible material.

5 In accordance with the present invention, the conventional single axially opening Venturi passage, such as shown in the copending application, Serial No. 487,689, filed by Warren H. Farr on May 20, 1943, has been replaced by a multi-jet rotary device 13.

To this end, the rearward end of the casing 5 is slightly reduced in diameter and provided with an internal shoulder 14. Inserted from the rearward end of the casing and seated against the shoulder 14 is an annular ball thrust bearing 15. The cylindrical rotary device 13 seats against the outer race of the bearing 15 and is mounted within the rearward end of the casing for free rotation by means of circumferentially surrounding rollers 16, commonly known as needle bearings, the bearings 16 engaging with the inner wall of the rear end of the casing 5 and being seated in a circumferential recess 17 formed in the peripheral wall of the rotary device 13.

15 The device 13 is retained within the casing by means of a radially inwardly flanged ring 22 externally threaded to the end of the casing as shown in the drawing.

20 The rotary device 13 is provided with a plurality of uniformly circumferentially spaced Venturi passages 18 arranged therein at an angle to the axis of the device 13. The passages 18 may be formed by drilling and then taper reaming the drilled openings from the opposite sides of the rotary device to provide the restriction 19 in the passages 18.

25 It will be obvious that the flow through the passages 18 of the products of combustion of the combustible propelling charge will, by reason of the angularly arranged passages 18, cause the device 13 to rotate. Since the device 13 is coaxial with the casing 5 and the gases discharge through the equally spaced jets, each the same distance from the axis of rotation, the gases will leave the device in an annular rotating stream truly coaxial with the casing thus insuring a uniform annular propelling pressure at all times.

30 In order to prevent the building up of a pressure within the casing prematurely which might tend to rupture the casing before the device has left the projector and thereby cause serious damage, the rotary device 13 is provided with a central passage 20 which is counterbored at its inner end to receive a plate 21 having a press fit therewith. The plate 21 is of less yield strength than

the casing wall and is of such predetermined strength that in the event of the building up of abnormal or excessive pressures within the casing, it will rupture or blow out to relieve the pressure within the casing before it can reach a value which will rupture the casing.

The present invention is applicable to any reaction propulsion device whether it be for an explosive projectile, a chemical device or any other arrangement adapted to be projected through space.

Various changes may be made in the detailed construction and arrangement of the parts described without departing from the spirit and substance of the invention, the scope of which is defined by the appended claims.

What is claimed is:

1. In a reaction propulsion device, a casing for housing a combustible propelling charge, a cylindrical member within one end of said casing, anti-friction bearing means within said end in surrounding relation with respect to said member for supporting said member for free rotation,

an annular end thrust bearing within said end in advance of said member and engaged therewith, and means secured to said end for retaining said member in said end, said member having a plurality of discharge passages extending longitudinally therethrough, said passages being inclined relative to the axis of rotation of said member and said axis of rotation being coincident with the axis of said casing.

2. In a reaction propulsion device, a casing for housing a combustible propelling charge, a cylindrical member within one end of said casing and having a plurality of circumferentially spaced jet passages extending therethrough into communication with the interior of said casing, said member having an axial opening therein, and a plate closing said opening at the end adjacent the interior of said casing, said plate being of a material having a yield strength less than the yield strength of said casing whereby incident to excessive pressures within said casing said plate will rupture prior to said casing.
